J. A. PAYETTE

BRACELET

Filed April 9, 1927

UNITED STATES PATENT OFFICE.

JOSEPH A. PAYETTE, OF ATTLEBORO, MASSACHUSETTS, ASSIGNOR TO S. O. BIGNY COMPANY, OF ATTLEBORO, MASSACHUSETTS, A CORPORATION OF MASSACHUSETTS.

BRACELET.

Application filed April 9, 1927. Serial No. 182,291.

This invention relates to a bracelet of the flexible extension type; and has for its object to provide in such a bracelet connected units each composed of guide and slide links of an improved construction which may be quickly manufactured and easily assembled with the minimum amount of stock for the required strength.

A further object of the invention is to provide a guide link having side walls with a connecting cross bar at one end only, the opposite ends being secured against separating movement by means engaging a spring which is guided between the side walls.

A still further object of the invention is the provision of a band shaped slide link having an end wall of double thickness and being sufficiently resilient to permit the cross bar of the guide link of the next adjacent unit to be detached therefrom by movement between the double thickness of the stock forming the end wall of the slide link.

With these and other objects in view, the invention consists of certain novel features of construction as will be more fully described, and particularly pointed out in the appended claims.

In the accompanying drawings:

Figure 1 is a perspective view with portions broken away showing two units of the bracelet extended and connected together.

Figure 2 is a perspective view of the guide link.

Figure 3 is a sectional view of the guide link with a spring mounted therein.

Figure 4 is a perspective view of the slide link.

Figure 5 is a central sectional view on line 5—5 of Figure 4.

Figure 6 is a perspective view of the spring.

Figure 7 is an end view thereof.

Figure 8 is a central sectional view of two units connected together.

Figure 9 is a sectional view on line 9—9 of Figure 10.

Figure 10 is a sectional view at right angles to that shown in Figure 8.

Figure 11 is a side elevation illustrating the manner of distorting the slide link in detaching the guide link therefrom.

It is found desirable in the manufacturing

of flexible bracelets to provide a series of 55 units which may be detachably connected together and of a construction which may be easily and quickly formed with the minimum amount of stock consistent with strength to resist the strains in ordinary 60 usage; and in order to provide a bracelet having these qualities, I have formed a guide link having channel shaped side walls connected at one end only by a crossbar and provided with a spring substantially rectangular in cross section to fit and be guided in the channels of the side walls with fingers on the free ends of the side walls, bent into the spring to retain the same in position and at the same time prevent a separating move- 70 ment of the unconnected ends of the channeled walls and I have connected these guide links together by slide links each having an end wall of double thickness through which the crossbar of the guide link may 75 be passed by resilient flexing of the slide link to detachably connect the units together and the following is a detailed description of one construction by which these advan- 80 tageous results may be accomplished:

With reference to the drawings, 10 designates a guide link formed of side walls 11 each having inwardly extending flanges 12 forming the same channel shape in cross section and connected by a cross bar 13 at one 85 end only. Within this guide link 10 there is slidably mounted between the edges of the flanges 12 a slide link 14 which is substantially band shape with one end wall formed of double thickness of stock 15 and 90 16 spaced apart slightly as illustrated in Figure 4, with the lip 17 lying in the depression 18 formed by an offset portion 19 in the rear wall 20 of the slide link so that the lip may be disposed in substantially the 95 same plane as the rear wall 20 to make the back even in appearance.

The slide link 14 is prevented from displacement in its position between the flanges 12 by a spring 21 of a width to extend into 100 the channels as illustrated in Figure 5 and having right angularly bent corner portions 22 to form the same substantially rectangular in cross section to fit snugly within the channels 23 of the opposite side walls to 105 be guided therein. Fingers 24 are provided on the unconnected ends of the side walls 11 of the guide link and are folded into

the spring 21, as illustrated in Figure 3, to retain the spring in the guide link and at the same time these fingers hold the unconnected ends of the guide link from separating or spreading. When the bracelet is expanded the wall 25 of the slide link brings up against the spring 21, as illustrated in Figure 10, to limit its expanding movement.

10 The slide link is disconnected from the guide link by first swinging the guide link up at substantially a right angle, bringing its cross bar 13 up into position to slide past the upturned end portion 16 then to 15 swing forwardly to pry open or separate the double walls and then to slide down and out past the lip 17 all as will be apparent from Figures 8 and 11, the reverse operation being followed for the attachment of the units 20 one to the other.

By providing a spring of the extreme width of the guide link, the same not only serves to guide and prevent displacement of the slide link therein but also being of the 25 largest size possible for the unit in which it is mounted serves to better resist the strains of intermittent expansion and contraction of the bracelet and retain its resiliency a greater length of time than 30 where a spring of smaller diameter is used.

From the foregoing it will be seen that I have provided a bracelet which has many advantages and is of simple construction to be easily and quickly operated.

35 The foregoing description is directed solely towards the construction illustrated, but I desire it to be understood that I reserve the privilege of resorting to all the mechanical changes to which the device is susceptible, the invention being defined and limited only 40 by the terms of the appended claims.

I claim:

1. A bracelet chain comprising a series of 45 units connected together, each comprising a U-shaped guide link and a connecting slide link, a spring guided by said walls and acting between said links to press them to contracted position, and means engaging the spring for holding it between the side arms 50 of the U link and also preventing the free ends of the arms from separating.

2. A bracelet chain comprising a series of 55 units connected together, each comprising a U-shaped guide link and a connecting slide link, said guide link having oppositely disposed channel shaped side walls with a cross bar connecting one end only, a spring acting between said links of a width to extend into the channels of said opposite walls 60 to be guided thereby, and means at the unconnected ends of said walls to engage the spring and retain it within said channel walls and also prevent the free ends of the channel walls from spreading.

3. A bracelet chain comprising a series of 65 units connected together, each comprising a guide link and a connecting slide link, said guide link having oppositely disposed side walls with a cross bar connecting said walls at one end only, a spring guided by 70 said walls and acting between said links to press them to contracted position, and fingers on the unconnected ends of said walls folded into said spring to retain the spring in position and at the same time prevent 75 said walls from spreading outwardly.

4. A bracelet chain comprising a series of 80 units connected together, each comprising a guide link and a connecting slide link, said guide link having oppositely disposed channel shaped side walls with a cross bar connecting one end only, a spring acting between said links of a width to extend into the channels of said opposite walls to be 85 guided thereby, and fingers on the unconnected ends of said walls folded into said spring to retain the spring in position and at the same time prevent said walls from spreading outwardly.

5. A bracelet chain comprising a series of 90 units connected together, each comprising a guide link having channel shaped side walls with flanges extending at substantially right angles to the walls, a spring folded to have 95 right angularly disposed portions and substantially rectangular in cross section to fit and extend between said channel walls and be guided thereby, a slide link of a width substantially the width between the channel flanges and slidably therebetween and guided 100 against displacement from between said flanges by said spring.

6. A bracelet chain comprising a series of 105 units connected together, each comprising a guide link having trough shaped side walls, a spring folded to substantially fit the shape 110 of the trough and of a width to extend into and between the troughs and be guided thereby, and a slide link guided in its sliding movement by the edges of the trough-shaped side walls and prevented from displacement between the edges by said spring.

7. A bracelet chain comprising a series of 115 units connected together, each comprising a guide link having a cross bar at one end and band shaped slide link slidably relative thereto with portions overlapping to form two parallel substantially contiguous end walls; said slide link being resilient to permit it to be distorted and allow the cross 120 bar to be moved between the parallel walls over the top of the inner one to be connected to or disconnected therefrom.

8. A bracelet chain comprising a series of 125 units connected together, each comprising a guide link having a cross bar at one end and a band-shaped slide link slidably relative thereto with portions overlapping and

forming an end wall of double thickness with a lip extending along the rear wall, the portion of the rear wall over which the lip extends being inwardly offset to permit the 5 lip to lie in substantially the same plane with the rear wall, said slide link being sufficiently resilient to permit the cross bar

of the next guide link to be detachably connected thereto by movement between said double thickness of end wall and between 10 said lip and offset portion.

In testimony whereof I affix my signature.

JOSEPH A. PAYETTE.
